(57) **CLAIM**

The ornamental design for a cabinet as shown and described.

DESCRIPTION

FIG. 1 is a front, left, top perspective view of a first embodiment of the cabinet showing our design;

FIG. 2 is a front elevation view thereof;

FIG. 3 is a rear elevation view thereof;

FIG. 4 is a top view thereof;

FIG. 5 is a bottom view thereof;

FIG. 6 is a left-side view thereof;

FIG. 7 is a right-side view thereof;

FIG. 8 is a front, left, top perspective view thereof with a door of the cabinet open;

FIG. 9 is a front, right, top perspective view of a second embodiment of the cabinet showing our design;

FIG. 10 is a front elevation view thereof;

FIG. 11 is a rear elevation view thereof;

FIG. 12 is a top view thereof;

FIG. 13 is a bottom view thereof;

FIG. 14 is a left-side view thereof;

FIG. 15 is a right-side view thereof; and,

FIG. 16 is a front, right, top perspective view thereof with a door of the cabinet open.

Portions of the cabinet shown in dash-dash broken lines and light rays emitted from a lighted rim of the cabinet's door also shown in dash-dash broken lines form no part of the claimed design. Dash-dot-dash boundary lines define a boundary between claimed and unclaimed portions of the cabinet design and form no part of the claimed design.
